UNITED STATES PATENT OFFICE.

SILAS E. WHITE, OF WATERTOWN, NEW YORK.

WATCHMAN'S SHOT-PROOF BOX.

SPECIFICATION forming part of Letters Patent No. 517,086, dated March 27, 1894.

Application filed October 15, 1892. Serial No. 449,016. (No model.)

To all whom it may concern:

Be it known that I, SILAS E. WHITE, of Watertown, in the county of Jefferson, in the State of New York, have invented new and useful 5 Improvements in Protectors for Watchmen, of which the following, taken in connection with the accompanying drawings, is a full, clear, and exact description.

My invention relates to improvements in 10 bullet and bomb-proof chambers or compartments applicable for use in express cars, banks and other vehicles or buildings in which it is desired to provide a device of this kind for the protection of a guard or watchman; and it has for its object the production 15 of an armored chamber or compartment, simple in construction and operation, and efficient, durable and practical in use; and to this end it consists, essentially, in an outer 20 case or shell, supports at the opposite extremities of the case or shell for permitting the same to be revolved in order that the guard or watchman on the interior may face in any direction, and in the detail construction 25 and arrangement of the parts, all as hereinafter more particularly described and pointed out in the claims.

In describing this invention, reference is had to the accompanying drawings, forming a 30 part of this specification, in which, like letters indicate corresponding parts in all the views.

Figure 1 is a vertical elevation, partly in 35 section, of my improved invention, illustrating its general construction and arrangement. Fig. 2 is a vertical sectional view, taken on line 2—2, Fig. 1, the door being illustrated in its normal closed position by full lines, and in its open position by dotted lines. Fig. 3 40 is an enlarged transverse horizontal sectional view, taken on line 3—3, Fig. 1. Fig. 4 is an enlarged detail vertical sectional view of the upper end of the chamber or compartment, illustrating particularly the means for locking 45 the outer case or shell of the compartment from revolution, and for permitting said case or shell to revolve. Fig. 5 is an enlarged inverted sectional view, taken on line 5—5, Fig. 4, for clearly showing the engaging face 50 at the upper end of the case or shell of the compartment or chamber. Fig. 6 is a top plan view of the detached sleeve mounted

upon the inner end of the supporting spindle for the case or shell and operating to lock said case or shell from movement, or to aid 55 the operator in rotating the same; and Fig. 7 is an isometric perspective of the hinged support for the door of the case or shell.

It is well known that guards and watchmen, and particularly express messengers are 60 frequently attacked by robbers, well supplied with fire arms, and, owing to lack of suitable protection, are either disabled or killed, or compelled to yield to the robbers who are then free to remove the treasure in the care 65 of the guards or watchmen. By my invention I provide a protecting chamber or compartment having bullet and bomb-proof walls into which the guard or watchman can quickly 70 and easily enter upon the slightest alarm or indication of the presence of robbers, &c., and can then view the entire room or car containing the treasure without any liability of injury, and can, while thus protected, shoot with accuracy any persons entering the room 75 without permission. My protecting chamber or compartment consists, essentially, of an outer case or shell —A—, and supports —B— 80 —C— for the upper and lower extremities of the case or shell. The case or shell —A— is formed of sheet-steel or boiler iron of sufficient thickness and strength to resist the entrance and action of bullets or bombs, and when intended for use in express cars, banks and other places of limited dimensions, its 85 central portion —a— is constructed in the form of an inverted truncated cone and its upper and lower extremities —a'—a²— are conically shaped, tapering outwardly from the central portion —a—. Experience shows 90 that a shell of this shape practically and efficiently resists the entrance or action of bullets and bombs, since curved and inclined surfaces are presented to the impingement of the bullets or bombs, and is easily, practically and economically manufactured. I do 95 not, however, restrict my invention to a case or shell of this precise form, since it is evident that its form may be varied to conform to the designer's taste, or the shape and construction of the car or room to be provided therewith. Although the case or shell —A— 100 may be of any desired size, or proportion, it is preferably formed, as illustrated, of a pro-

portion and size suitable for permitting a single man to use small fire arms with ease, as it is usually desired to restrict to the utmost the amount of room occupied by the 5 protecting chamber or compartment in order that the room may be used for other purposes. The supports —B—C— for the opposite ends of the case or shell —A— may be of any desirable form and construction to practically and efficiently support said case, but they are preferably constructed, as illustrated, so as to permit the case to be revolved practically and freely from its interior in order that the occupant may view any portion 10 of the car or room in which the case or shell is arranged.

—A'— is a door of suitable form and size for closing an opening —A²— in the wall of the central portion —a— of the case or shell 20 —A—. The opening —A²— is formed with an endless flange —A³— and the door —A'— with a similar flange or rabbet —A⁴— adapted to rest against the outer face of the flange or rabbet —A³—.

—D— is a hinged connection for supporting the door —A'—, and, as preferably constructed, and as best seen at Figs. 2, 3 and 7, the connection —D— consists of a plate having one end hinged at —a⁵— to an arm —A⁵— 25 extending inwardly from the inner face of the door —A'— and its other end hinged at —a⁴— to a plate —A⁶— on the inner face of the case —A— at one side of the opening —A²—. In opening the door, the connection, 30 —D— swings outwardly upon the hinge pin —a⁴— and the door —A'— swings upon the hinge pin —a³— until the left-hand edge —a⁵— of the door engages the case —A— at the left-hand of the opening —A²— as clearly 35 seen at Figs. 2 and 3. The door —A'— is automatically closed by a counter-weight —E— connected to one end of a flexible cord —e— passed over a guide-pulley —e'— and having its opposite end secured at —e²— to the inner face of said door. The guide-pulley —e'— is journaled in a bracket —e³— on the inner face of the case or shell —A—. 40

—F— is a brace for normally holding the door —A'— open against the action of the 50 counter-weight —E— when the guard or watchman is at the outside of said case. The brace —F— preferably consists of the inner section —f— hinged at —f'— to the case or shell —A—, and the outer section —f²— having one end hinged at —f³— to the section 55 —f— and the other end adapted to engage a shoulder —a⁶— on the inner face of the door —A'—. The sections —f—f²— are disposed in planes one above the other and the inner 60 face of the section —f— and the outer face of the section —f²— are preferably concavely curved in order that said sections may, in their normal position, lie closely against the wall of the case —A— and occupy the least 65 possible room.

In entering the case or shell —A—, the

guard or watchman rocks the section —f— of the brace —F— on the pivot —f'— and thereby rocks the outer end of the section —f²— from operative engagement with the shoulder —a⁶— on the door —A'— whereupon the weight —E— immediately and automatically closes said door and the operator then rocks the brace section —f²— upon the pivot —f'— to its normal position beneath or above 75 the section —f— as clearly seen at Fig. 3.

The door —A— is locked in position by any suitable form of catch, here shown as consisting of a lever —G— hinged at one end to the interior of the case by a hinge pin —g— and as adapted to removably engage an arm —G'— 80 on the inner face of the door —A'—.

—H— is a chamber formed in the lower end of the case or shell —A—, and —h— the top wall for said chamber which forms the support for the occupant. The wall —h— is preferably provided with any suitable construction of trap-door —h'— for permitting entrance to the chamber —H—. This chamber —H— forms a convenient receptacle for arms, 85 ammunition, &c., and, as a further support for such articles, and for a suitable lantern I provide shelves —I—I'— which project from the inner wall of the case at a convenient height above the wall —h—.

—a⁷— represents ventilating openings in the upper extremity —a'— of the shell —A—; —a⁸— sight or loop openings beneath the former openings for enabling the occupant of the shell —A— to watch the advance of intruders or others, and to shoot through the wall of the shell with accuracy and precision; and —a⁹— similar sight or loop openings in the cover or door —A'—. The latter openings, —a⁹—, are closed by outside shutters 100 —a¹⁰— which are operated from the interior of the shell —A— to open and close said openings. These shutters are mounted on spindles —a¹¹—, to the inner ends of which are secured levers —a¹²— which are rocked upwardly or downwardly to open or close the openings —a⁹—. The support —B— consists, preferably, of a trunnion projecting from the central portion of a bearing face —a¹³— at the lower extremity of the case or 110 shell —A— and is adapted to enter a socket —B'— in a step or bearing —B²— suitably secured by fastening means —b—b— to a supporting frame bar —B³—.

—a¹⁴—b— are grooves formed, respectively, in the face —a¹³— of the case or shell —A— and the top face of the step or bearing —B²— for receiving anti-friction balls —a¹⁵—.

The support —C— for the upper end of the shell —A— consists of a non-revolving spindle having its upper end secured by fastening means —c—c— to a suitable supporting bar —C'— and its lower end inserted within the upper end of the case —A— through an opening —A⁷— in the upper extremity of the 125 case —A—.

—A⁸— is an engaging face at the upper

extremity of the case —A—, which, as best seen at Fig. 5, is formed with a series of apertures or sockets —A⁹—.

—C²— is a lock movably mounted within 5 the case —A— on the inner end of the support or spindle —C—. As preferably constructed, this lock, best illustrated at Figs. 2, 4 and 6, consists of a sleeve having a projecting arm —C³— provided with an engaging 10 tooth —C⁴— adapted to enter one of the sockets —A⁹— of the engaging face —A⁸—.

Projecting from the supporting spindle —C— is a lug —C⁵— registered with an elongated groove —C⁶— in the sleeve —C²— for 15 preventing said sleeve from revolution. A spring —C⁷— interposed between a shoulder —C⁸— on the supporting spindle —C— and the adjacent or lower face of the sleeve —C²— normally forces said sleeve —C— upwardly 20 and engages the tooth —C⁴— thereon with one of the sockets —A⁹—. The case or shell —A— is revolved, as previously described, upon its trunnion —B'— and around the non-revolute spindle —C—, but is normally 25 locked from revolution by the normal engagement of the tooth —C⁴— with the engaging face —A⁸— at the upper end of said shell. As the sleeve or lock —C²— is forced downwardly along the spindle —C— against the 30 action of the spring —C⁷—, the tooth —C⁴— is withdrawn from engagement with the socket —A⁹—. The operator on the interior of the case or shell —A—, who stands upon the supporting wall —h—, is then free to revolve the 35 case —A— by pushing against the non-revolute sleeve —C²—, and to facilitate this action, the sleeve —C²— is formed with hand-engaging arms —C⁹—. When the case or shell is revolved to the desired position, the 40 operator releases the sleeve —C²— and the spring —C⁷— automatically engages the same with one of the apertures —A⁹— and firmly locks the case or shell —A— in its adjusted position and prevents any one on the exterior 45 of said shell or case from revolving the same against the will of the guard or watchman within the case or shell.

The described construction of supports for the lower and upper extremities of the case 50 or shell —A— are simple in construction and operation, permit the same to be revolved with great ease and convenience from the interior, and absolutely prevent the revolution of the case or shell from the exterior.

55 In order that the guard or watchman within the case or shell —A— may alarm others of his peril, I provide a bell —J— which is mounted in any suitable locality, as an adjoining car or room, a battery —j—, a positive wire —j'— having one end connected to the positive pole of the battery —j—, and a negative wire —j²— connected to the bell —J— and having one end secured to the negative pole of the battery —j—. The opposite ends 60 of the wires —j'— —j²— are passed within the spindle —C— which is preferably formed hollow and are secured to positive and negative

terminals —j³— —j⁴— mounted in a plate —j⁵— on the interior of the lower end of said spindle. Beneath the plate —j⁵— a second plate —j⁶— 70 and guided through the plate —j⁶— is the plunger of a push button or cut-out controller —j⁷— having a shoulder —j⁸— interposed between the plates —j⁵— —j⁶—. A spring —j⁹— normally forces the shoulder —j⁸— against 75 the guide plate —j⁶— and when the push button is forced inwardly, its shoulder —j⁸— encounters the terminals —j³— —j⁴— and completes the circuit through the bell —J—, battery —j— and wires —j'— —j²— thus sounding 80 an alarm in the locality provided with said bell.

The alarm, the electric circuit and the circuit closer for operating the same have been but briefly described as the same form no 85 part of my present invention, although they are obviously extremely applicable for use therewith.

The operation of my invention will be readily understood from the foregoing description 90 and upon reference to the drawings and it will be noted that a guard or watchman upon the least sign of danger, may quickly and easily protect himself within my improved shell or compartment, and may view the approach or entrance of intruders and defend himself by fire-arms without the slightest liability of danger. It will also be understood that my improved protecting chamber or compartment is simple and economical in construction, is easily operated, and is practical, durable and efficient in use. The detail construction and arrangement of said chamber 95 or compartment may, however, be greatly varied without departing from the spirit of my 100 invention, hence I do not herein specifically limit myself to such exact detail construction and arrangement.

Having thus fully described my invention, what I claim as new, and desire to secure by 110 Letters Patent, is—

1. A protecting chamber or compartment comprising an outer casing or shell provided with an opening at one extremity and a trunnion at its opposite extremity, a spindle passed 115 through said opening for supporting the extremity provided therewith, and a support or bearing for receiving said trunnion and supporting the opposite extremity of the casing, substantially as and for the purpose set forth. 120

2. A protecting chamber or compartment comprising an outer casing or shell formed with contracted extremities having inclined outer faces and provided with an opening at one extremity and a trunnion at its opposite 125 extremity, a spindle passed through said opening for supporting the end of said casing provided therewith, and a support or bearing for receiving said trunnion and supporting the opposite end of the casing, substantially as 130 and for the purpose set forth.

3. A protecting chamber or compartment comprising an outer casing or shell formed with contracted extremities and a central por-

tion having inclined outer faces, and provided with an opening at one extremity and a trunnion at its opposite extremity, a spindle passed through said opening for supporting the extremity provided therewith, and a support or bearing for receiving said trunnion and supporting the opposite extremity of the casing, substantially as and for the purpose specified.

4. A protecting chamber or compartment comprising an outer revoluble casing or shell, supports at the opposite extremities of said casing for permitting its rotation, a stationary spindle projecting through one extremity of said casing within the same, and a hand engaging portion provided on said spindle whereby the casing may be rotated, substantially as set forth.

5. A protecting chamber or compartment comprising an outer casing or shell formed with contracted extremities and a central portion having inclined outer faces, and provided with an opening at one extremity and a trunnion at its opposite extremity, a spindle passed through said opening for supporting the extremity provided therewith and provided with a hand engaging portion C^o, and a support or bearing at the opposite extremity for receiving said trunnion and supporting said extremity of the casing, substantially as and for the purpose specified.

6. A protecting chamber or compartment comprising an outer revoluble case or shell having an engaging face on the interior of said case, at one end, a supporting stationary spindle, projecting through said end and a lock movably mounted on the spindle in proximity to said face and formed with an engaging tooth for normally engaging said face of the case and locking the same from movement, substantially as and for the purpose specified.

7. A protecting chamber or compartment comprising an outer revoluble case or shell having an internal engaging face at one end and provided with an opening through said end, and an outer bearing face at its opposite end, a supporting stationary spindle having its lower end inserted within the case or shell through said opening, a lock movably mounted on the spindle in proximity to said engaging face and formed with an engaging tooth for normally engaging said face of the case and locking the same from movement, a trunnion projecting from the central portion of the bearing face at the lower extremity of the case, a step or socket for receiving said trunnion and supporting the corresponding end of the casing and provided with an upper bearing face, and anti-friction balls interposed between the bearing faces of said case and step, substantially as and for the purpose set forth.

8. A protecting chamber or compartment comprising an outer revoluble case or shell having an engaging face on the interior of one extremity, a supporting stationary spindle projecting through said extremity, a lock

movably mounted on the spindle in proximity to said engaging face and formed with an engaging tooth for normally engaging said face and locking the same from movement, and a lug provided on the inner end of said spindle for retaining said lock in operative position, substantially as and for the purpose set forth.

9. A protecting chamber or compartment comprising an outer revoluble case or shell having an internal engaging face, at one extremity, a supporting stationary spindle, a lock movably mounted on the spindle in proximity to said face and formed with an engaging tooth, and a spring for normally engaging said tooth with the inner engaging face of the case and locking the same from movement, substantially as and for the purpose specified.

10. A protecting chamber or compartment comprising an outer revoluble case or shell having an internal engaging face, at one extremity a supporting stationary spindle extending within the outer case or shell, in proximity to said face a sleeve movable lengthwise on the spindle and formed with a tooth for engaging the internal engaging face of the case, a lug on the spindle for preventing revolution of the sleeve thereon, a spring for normally elevating the sleeve and forcing its tooth into engagement with the internal engaging face of the case, substantially as and for the purpose set forth.

11. A protecting chamber or compartment comprising an outer revoluble shell or case having an internal engaging face, at one extremity, a supporting stationary spindle extending within the outer case or shell, in proximity to said face a sleeve movable lengthwise on the spindle and formed with a tooth for engaging the internal engaging face of the case, a lug on the spindle for preventing revolution of the sleeve thereon, a spring for normally elevating the sleeve and forcing its tooth into engagement with the internal engaging face of the case, and a hand engaging portion upon the sleeve whereby the sleeve may be drawn out of engagement with the internal engaging face of the case for permitting revolution of the case, substantially as and for the purpose set forth.

12. A protecting chamber or compartment comprising an outer case or shell formed with an opening in its wall, a door for opening and closing said opening, an inwardly projecting arm on the door, and a link or support having one end hinged to the arm on the door and the other hinged to the inner face of the case or shell, substantially as and for the purpose specified.

13. A protecting chamber or compartment comprising an outer case or shell formed with an opening in its wall, a door for opening and closing said opening, an inwardly projecting arm on the door, a link or support having one end hinged to the arm on the door and the other hinged to the inner face of the

case or shell, a guide within the case or shell, and a flexible connection passed over said guide and having one end secured to the door and the other to a counter-weight, substantially as and for the purpose set forth.

14. A protecting chamber or compartment comprising an outer case or shell formed with an opening in its wall, a door for opening and closing said opening, an inwardly projecting arm on the door, a link or support having one end hinged to the arm on the door and the other hinged to the inner face of the case or shell at one side of the opening, a movable locking bar or latch hinged to the inner face of the case at the opposite side of the opening, and a shoulder on the door for engaging the free end of said locking bar or latch, substantially as and for the purpose specified.

15. A protecting chamber or compartment comprising an outer case or shell formed with an opening in its wall, a door for opening and closing said opening, a hinged connection having one end secured to the inner face of the door and the other to the inner face of the case at one side of said opening, and a flexible brace or connection between the door and

the inner face of the case at the opposite side of said opening, substantially as and for the purpose set forth.

16. A protecting chamber or compartment comprising an outer case or shell formed with an opening in its wall, a door for opening and closing said opening, a hinged connection having one end secured to the inner face of the door and the other to the inner face of the case at one side of said opening, and a brace consisting of inner and outer sections, the inner section being hinged to the inner face of the case at the opposite side of said opening, and the outer section being hinged to the outer end of the former section and having its outer end adapted to engage the door, substantially as and for the purpose specified.

In testimony whereof I have hereunto signed my name, in the presence of two attesting witnesses, at Syracuse, in the county of Onondaga, in the State of New York, this 14th day of June, 1892.

SILAS E. WHITE.
